(Cl. D91—1)

To all whom it may concern:

Be it known that I, Donald E. Davidson, a citizen of the United States of America, residing in the city of Los Angeles, in the county of Los Angeles, State of California, have invented a new, original, and ornamental Design for a Valve Body for Swing Spout Sink Faucet, of which the following is a specification, reference being had to the accompanying drawing, forming a part thereof.

Fig. 1 is a perspective view of a valve body for a swing spout sink faucet, showing my new design;

Fig. 2 is a plan view thereof;
Fig. 3 is a front elevational view thereof; and
Fig. 4 is an end elevational view thereof.

I claim:

The ornamental design for a valve body for swing spout sink faucet, substantially as shown.
DONALD E. DAVIDSON.
